UNITED STATES PATENT OFFICE.

FRANK J. GIBBONS, OF WORCESTER, MASSACHUSETTS.

VALVE GRINDER.

Application filed August 24, 1921. Serial No. 495,129.

To all whom it may concern:

Be it known that I, FRANK J. GIBBONS, a citizen of the United States, residing at Worcester, in the county of Worcester and 5 State of Massachusetts, have invented a new and useful Valve Grinder, of which the following is a specification.

This invention relates to a valve grinder designed for use in grinding the valves of 10 internal combustion engines. In this operation it is desirable to give a valve a short oscillatory movement and to constantly change or advance the field of such movement. This combination of angular advance 15 with oscillatory movement has been found best adapted to produce true surface contact between the valve and its seat.

It is the general object of my invention to provide mechanism by which this combined 20 movement may be produced in a most efficient and satisfactory manner. The reversal of movement is smoothly and easily accomplished and the whole mechanism operates without objectionable vibration.

25 A further object of my invention is to provide means by which the device may be readily adapted to furnish a simple rotary movement when desired.

With these general objects in view, an important feature of my invention relates to 30 improved means for producing the combined angular advance and oscillatory movement. In the preferred form, this is accomplished by the use of balls or rollers mounted between 35 driving members having oppositely moving bearing surfaces and provided with spaced recesses therein. The disc or carrier for the balls or rollers is fixed on the shaft to be oscillated and receives movement through 40 the balls or rollers from rotating members alternately.

My invention further relates to arrangements and combinations of parts which will be hereinafter described and more particularly pointed out in the appended claims.

45 A preferred form of my invention is shown in the drawings in which—

Fig. 1 is a sectional elevation of my improved valve grinder;

50 Fig. 2 is a detail elevation showing certain parts in a different position;

Fig. 3 is a bottom view of the bearing plate of the upper driving member;

55 Fig. 4 is a plan view of the bearing plate of the lower driving member;

Fig. 5 is a plan view of the disc or carrier for the balls or rollers;

Fig. 6 is a partial plan view of a modified form of carrier and roller, and

Fig. 7 is a detail sectional view taken 60 along the line 7—7 in Fig. 6.

Referring to the drawings, I have shown a valve grinder comprising a casing having a lower portion or frame 10 and a cover 11 secured thereto by binding screws 12. A 65 shaft 13 is rotatable in bushings 14 and 15 threaded into the casing members 10 and 11 respectively. A reversible valve-engaging tool 16 is detachably secured in a slot in the lower end of the shaft 13. Binding 70 or lock nuts 17 and 17^a are provided for securing the bushings 14 and 15 in adjusted position.

A lower driving member 18 is freely rotatable upon the shaft 13 and is axially positioned within the casing by the inner end 75 of the bushing 14. An upper driving member 19 is similarly positioned by the inner end of the bushing 15. The driving members 18 and 19 are provided with bevel gear 80 teeth oppositely engaging a driving bevel pinion 20 fixed on a short shaft or stud 21 rotatable in a bearing in the frame 10 and having a handle 22 secured to the outer end thereof. Manual movement of the handle 85 revolves the driving members 18 and 19 continuously in opposite directions.

A disc or carrier 23 is fixed to the shaft 13 between the driving members 18 and 19 and is provided with recesses 24 (Fig. 5) 90 within which are seated balls 25. The driving members are preferably provided with hardened steel bearing plates 26 and 27 riveted or otherwise secured thereto. These plates are provided with shallow rounded or 95 cup-like recesses 28 (Fig. 4) and 29 and 30 (Fig. 3).

The driving members are so adjusted by the bushings 14 and 15 that there is just sufficient space between the plates 26 and 100 27 so that a ball seated in one of the recesses in one bearing plate will just clear the flat surface of the other bearing plate.

The operation of the mechanism thus far described is as follows:—Assuming that the 105 parts are positioned as shown in Fig. 1, with the balls 25 seated in the recesses 28 of the bearing plate 26, the lower driving member 18 is thus locked to the disc or carrier 23 and the shaft will be rotated 110

in unison with the angular movement of the member 18, the balls 25 rolling along the smooth surface of the bearing plate 27 between the recesses therein.

Such movement will continue until the balls 25 reach a pair of recesses 29 or 30 in the plate 27. The resistance of the valve to movement by the shaft 13 will then cause the balls to shift immediately to the recesses in the plate 27 of the upper driving member, and the latter member will immediately proceed to drive the balls in the opposite direction, carrying the disc 23 and shaft 13 along with them. As the circumferential distances between the holes 28 in the plate 26 are greater than the distances between the holes 29 and 30 in the plate 27, the movements of the disc and shaft in opposite directions are unequal and the field of oscillatory movement is gradually advanced. Furthermore, the unequal spacing of the recesses in the plate 27 causes the advance movements of the disc and shaft in one direction to be themselves irregular, thus giving a varied oscillatory advance movement to the valve.

It will be obvious that suitably tapered rollers may be substituted for the balls 25 and this alternate construction is indicated in Figs. 6 and 7, the construction and operation being otherwise similar to that already described.

The word "roller" as it occurs in the claims is understood to cover either spherical, cylindrical or tapered rolling elements.

It is sometimes desirable to continuously rotate the shaft 13 and for this purpose I provide the driving member 19 with axial grooves 31 (Fig. 3) adapted to receive balls 32 mounted in cross openings near the upper end of the shaft 13. The shaft is recessed to receive a plunger 33 having a groove 34, a shoulder 35 and a head 36. The upper end of the shaft 13 is notched or recessed at 37 to receive a cross pin 38 in the plunger 33 and the plunger is provided with a knurled end 39 by which it may be moved.

When the plunger 33 is fully inserted, as shown in Fig. 1, the driving member 19 is free to rotate on the shaft 13 as the balls 32 are received in the groove 34 and do not project beyond the surface of the shaft 13. At this time the cross pin 38 is seated in the notches 37.

When the plunger 33 is pulled upward, the balls 32 will be forced outwardly by the shoulder 35, entering the grooves 31 in the driving member 19 and locking the latter to the shaft 13. The plunger may be held in this position by turning the cross pin 38 so that it cannot enter the notches 37. The head 36 of the plunger prevents further withdrawal thereof and thus prevents displacement of the parts. When the shaft 13 is to be driven continuously, the bushing 14 is moved outward sufficiently to allow the

balls 24 to roll freely between the bearing plates 26 and 27.

It will thus appear that I have provided a valve grinder capable of producing an advancing irregular oscillatory movement with the use of very few and simple moving parts.

Having thus described my invention, it will be evident that changes and modifications may be made therein by those skilled in the art within the spirit and scope thereof as set forth in the claims and I do not wish to be otherwise limited to the details herein disclosed but what I claim is:—

1. A valve grinder comprising a casing, a shaft rotatably mounted in said casing, a pair of driving members freely rotatable on said shaft and having recesses in their adjacent bearing faces, means to continuously rotate said driving members in opposite directions, a roller, and a carrier therefor fixed to said shaft between said driving members, said roller entering the recesses in the two driving members alternately and thus connecting said carrier and shaft to said members alternately. 80

2. A valve grinder comprising a casing, a shaft rotatably mounted in said casing, a pair of driving members freely rotatable on said shaft and having recesses in their adjacent bearing faces, means to continuously rotate said driving members in opposite directions, a pair of rollers, and a carrier therefor fixed to said shaft between said driving members, said rollers entering recesses in said driving members alternately and thus alternately forming driving connections between each member and said carrier. 95

3. A valve grinder comprising a casing, a shaft rotatably mounted in said casing, a pair of driving members freely rotatable on said shaft and having recesses in their adjacent bearing faces, means to continuously rotate said driving members in opposite directions, a carrier fixed to said shaft between said driving members, and devices on said carrier adapted to enter said recesses and form driving connections with said members, the circumferential spacing of the recesses in one of said members being greater than the circumferential spacing in the other member, whereby the field of oscillation is gradually advanced. 110

4. A valve grinder comprising a casing, a shaft rotatably mounted in said casing, a pair of driving members freely rotatable on said shaft and having recesses in their adjacent bearing faces, means to continuously rotate said driving members in opposite directions, a carrier fixed to said shaft between said driving members, and devices on said carrier adapted to enter said recesses and form driving connections with said members, the circumferential spacing of the recesses in one of said members being unequal, 130

whereby the oscillatory movements in one direction are unequal in extent.

5. A valve grinder comprising a casing, a shaft rotatably mounted in said casing, a pair of driving members freely rotatable on said shaft and having recesses in their adjacent bearing faces, means to continuously rotate said driving members in opposite directions, a roller, a carrier therefor fixed to said shaft between said driving members, said roller alternately connecting said carrier and shaft to different driving members, and one of said driving members having 25 axial grooves therein, locking balls in said shaft, and means to force said balls outwardly into said grooves to lock said driving member to said shaft.
- 10 7. A valve grinder comprising a casing, a shaft rotatably mounted in said casing, a pair of driving gears freely rotatable on said shaft, means to continuously rotate said gears in opposite directions, a member fixed to said shaft between said gears, and means 30 to connect said member to said gears alternately and to hold said parts connected for unequal periods of rotation in one direction, thereby producing unequal advance movements in one direction. 35
- 15 6. A valve grinder comprising a casing, a shaft rotatably mounted in said casing, a pair of driving members freely rotatable on said shaft and having recesses in their adjacent bearing faces, means to continuously 40 rotate said driving members in opposite directions, a roller, a carrier therefor fixed to said shaft between said driving members,

said roller alternately connecting said carrier and shaft to different driving members, and one of said driving members having 25 axial grooves therein, locking balls in said shaft, and means to force said balls outwardly into said grooves to lock said driving member to said shaft.

7. A valve grinder comprising a casing, a shaft rotatably mounted in said casing, a pair of driving gears freely rotatable on said shaft, means to continuously rotate said gears in opposite directions, a member fixed to said shaft between said gears, and means 35 to connect said member to said gears alternately and to hold said parts connected for unequal periods of rotation in one direction, thereby producing unequal advance movements in one direction. 40

In testimony whereof I have hereunto affixed my signature.

FRANK J. GIBBONS.
